US00D854621S

(12) **United States Design Patent** (10) Patent No.: **US D854,621 S**
(45) Date of Patent: **** Jul. 23, 2019**

(54) **GAMING MACHINE DISPLAY CONFIGURATION**

(71) Applicant: **AGS LLC**, Las Vegas, NV (US)

(72) Inventors: **Rachel Marie Calhoun**, Atlanta, GA (US); **Karl Frederick Zedell, Jr.**, Alpharetta, GA (US); **Sigmund Lee**, Atlanta, GA (US)

(73) Assignee: **AGS LLC**, Las Vegas, NV (US)

(**) Term: **15 Years**

(21) Appl. No.: **29/646,448**

(22) Filed: **May 4, 2018**

Related U.S. Application Data

(62) Division of application No. 29/541,557, filed on Oct. 5, 2015, now Pat. No. Des. 818,048.
